INVENTOR
Michel Kraslavsky,

By C. P. Jepel
ATTORNEY.

UNITED STATES PATENT OFFICE.

MICHEL KRASLAVSKY, OF NEW YORK, N. Y., NOW BY CHANGE OF NAME MITCHELL KRASS.

MOTION-PICTURE FILM.

Application filed August 31, 1925. Serial No. 53,458.

This invention relates to motion picture films, and has for its primary object to provide an improved reinforcing means for the perforated edges of the film to prevent mutilation or tearing of the film in the engagement of the teeth of the feed and take-up sprocket wheels in the film perforations. It is the purpose of my present improvements to provide a reinforcement for the perforated edges of the film which is permanently bonded in the body of the film material and which may be readily applied in the process of manufacture of the film.

It is also an object of the invention to provide a reinforcing or strengthening means for the edges of the film which may be embodied or incorporated therein during the process of manufacture of the film whereby an indissoluble bond is effected between the gelatinous substance of the film and the reinforcing material.

It is a more particular object of the invention to provide a reinforcement for films in the form of a continuous strip of flexible material incorporated in the edge portions of the film intermediate of its opposite side faces so that the film itself protects the reinforcing material against excessive wear, and the film remains of uniform thickness throughout so that in rolling the film the surfaces of the superimposed film convolutions will have close contact with each other.

With the above and other objects in view, the invention consists in the improved motion picture film and in the several structural features thereof as will be hereinafter more fully described, illustrated in the accompanying drawing, and subsequently incorporated in the subjoined claims.

In the drawing, wherein I have illustrated one simple and practical embodiment of the invention, and in which similar reference characters represent corresponding parts throughout the several views,

Figure 1 is a plan view of a section of film provided with my improved reinforcement, and

Fig. 2 is a sectional view taken on the line 2-2 of Fig. 1.

In the operation of motion picture taking and projecting machines, an interrupted or step by step movement is imparted to the film past the light aperture by sprocket teeth or other mechanical means engaging the perforated edges of the film. By reason thereof, the edge of the film at the perforations frequently become badly torn or mutilated. Various means have been suggested for reinforcing the edges of the film, which however, have not been found entirely successful and are also more or less difficult of application.

It is the purpose of my present improvements to provide a reinforcement for the perforated edges of the film which is permanently bonded in the body of the film material and which may be readily applied in the process of manufacture of the film.

As herein shown, the film body indicated at 5 consists of a pyroxylin product such as celluloid, though other gelatinous materials than pyroxylin may be used. During the process of manufacture of the film and while the film material is in a plastic or semi-plastic state as it is flowed upon the film receiving surface, two relatively narrow strips of netted, woven or textile fabric such as a heavy grade of silk as indicated at 6, are fed in parallel relation with the film material so that these fabric strips occupy positions along the longitudinal borders of the film mass and intermediate of the opposite side faces thereof as clearly shown in Fig. 2 of the drawings. The film material entering the interstices of the fabric strips from opposite sides thereof, forms an indissoluble bond with said fabric reinforcing strips so that there is no possibility of separation of the individual fibers of said reinforcing strips from their interwoven relation with each other or from the body of the film material. Also, it will be observed that the completed film is of uniform thickness throughout its area and the opposite side faces thereof are perfectly smooth and uninterrupted.

After the reinforcing strips have thus been applied and the film material has cooled and set, the film is then run through a perforating machine to provide in the opposite edges thereof the spaced sprocket teeth receiving perforations 7 extending through the film and the intermediate reinforcing strips 6 incorporated therein. While I have referred to these reinforcing strips as preferably of silk or other fabric material, it is possible that other flexible non-fabric materials might be used, such for instance as tin foil or the like, and it will, therefore, be understood that in carrying out my invention, I do not in all cases desire to be restricted to the use of the fabric or textile reinforcement for the film edges.

It will be apparent that a film when reinforced in the manner above described is materially strengthened in its resistance to tensile strains thereby minimizing the possibility of breaking the film, while at the same time

a very strong reinforcement is provided for the individual film perforations so that said perforations will not be elongated by the sprocket teeth and the film torn or mutilated. Since the reinforcing strips are not applied to the surfaces of the film, but are incorporated within the body thereof, the reinforcing material itself is protected against excessive wear by the engagement of the feed or take-up sprocket teeth therewith and the possibility of the individual fibers of the reinforcing strips becoming separated and projecting from the film perforations is obviated. A reinforced motion picture film of this construction can be very inexpensively produced in the process of manufacture and no re-heating of the edges of the film or the use of cementitious material is required in the application of the reinforcement to the edges of the film. Further, since the side faces of the film are smooth and uninterrupted and said film is of uniform thickness throughout its area it can be closely coiled or wound in a roll with the surfaces of the superimposed film convolutions in uniform contact throughout with each other and since the reinforcement is contained within the body of the film, it is not subject to frictional wear in the rolling or unrolling of the film.

From the foregoing description considered in connection with the accompanying drawing, the construction and several advantages of my improved motion picture film will be clearly understood. As above suggested,

while I have herein disclosed one simple and practical embodiment of the invention, the same is nevertheless, susceptible of considerable modification both in the particular form of the reinforcing means employed and the structure thereof, and also in the manner of its application. Accordingly, it will be understood that I reserve the privilege of resorting to all such legitimate changes as may be fairly embodied within the spirit and scope of the invention as claimed. 45

I claim:

1. A motion picture film comprising a plastic film body, and relatively narrow and thin strips of woven silk fabric embedded in the longitudinal edge portions of the film body and being wholly enclosed by said film body, the body material entering into the meshes of the silk fabric.
2. An improved motion picture film comprising a pyroxylin film body, and relatively thin and narrow strips of flexible textile material having meshes therein into which the pyroxylin material enters to form an indissoluble bond, said strips being embedded within the longitudinal edge portions of the film body and being exposed only upon the opposite edge portions of said film body, said embedded fabric strips and the encasing edge portions of the film body being perforated. 63

In testimony that I claim the foregoing as my invention, I have signed my name hereto.

MICHEL KRASLAVSKY.
